SANDING DRUM PAD

Freeman S. Mitchell, San Diego, Calif.

Application December 9, 1937, Serial No. 178,997

7 Claims. (Cl. 51—194)

The present invention relates to sanding drum pads used on sanding machines and has for its primary object to provide a resilient rubber pad surrounding the drum beneath the sheet of sanding paper and provided with air channels embodying means for circulating air against the underside of the paper to cool the same during the rotation of the drum.

An object of the present invention is to provide a cooling attachment for sanding drums of this character which is efficient and reliable in performance, relatively inexpensive to manufacture, which may be easily and quickly installed in operative position upon the drum and otherwise well adapted for the purposes for which the same is intended.

Further objects and advantages reside in the details of construction as more fully hereinafter described and claimed, reference being had to the accompanying drawing forming part hereof, wherein like numerals refer to like parts throughout and in which:

Figure 1 is an end elevational view of the cooling pad and rim for attaching to the sanding drum.

Figure 2 is a transverse sectional view through the pad and drum, and

Figure 3 is a fragmentary plan view of the pad showing the diagonal arrangement of the channels.

Referring now to the drawing in detail, the invention comprises a sheet metal rim 5 having its side edges provided with down-turned flanges 6 in which openings 7 are formed for receiving bolts or the like for securing the rim in position to a sanding drum of conventional construction, (not shown).

A resilient rubber pad 8 is secured to the outer surface of the rim 5 by cementing, vulcanizing or in any other suitable manner, the outer surface of the pad being provided with alternate ribs 9 and channels 10 which extend diagonally across the outer surface of the pad, the channels, inwardly of the surface of the pad, being enlarged to provide passages 11 of substantially round shape in cross section and correspondingly forming the ribs 9 of substantially dove-tailed shape in cross section, as shown at 12.

The drum upon which the pad is mounted is intended to be rotated in the direction as shown by the arrow in Figure 1 of the drawing and the forwardly disposed end of the passages 11 have their front edges notched as shown at 13 and the rear edges of the channels are provided with outwardly projecting cups or vanes 14 to facilitate

the entrance of air into the passages during the rotation of the drum for the purpose of circulating the air transversely of the drum toward the opposite end of the passages.

The said opposite ends of the passages have their leading edges provided with outwardly projecting cups or vanes 15 and the rear edges notched as shown at 16 to facilitate discharge of the air therefrom, said cups 15 further serving to form a vacuum adjacent the discharge end 10 of the passages to facilitate the circulating of air through the same.

The sanding paper (not shown) is adapted to surround the pad with its ends clamped between the split ends 17 of the rim.

It is believed the details of construction and operation of the device will be readily understood from the foregoing without further detailed explanation.

Having thus described the invention what I claim is:—

1. A sanding drum pad adapted for positioning between the drum and abrasive sheet carried thereby, said pad having air channels therein for cooling the underside of the abrasive sheet 25 and means projecting from the ends of the channels for deflecting air into the channels.

2. A sanding drum pad adapted for positioning between the drum and abrasive sheet carried thereby, said pad having air channels in the surface thereof to provide contact for air with the underside of the sheet for cooling said sheet and cup-shaped deflectors projecting from the ends of the channels for deflecting air into the channels.

3. A sanding drum pad adapted for positioning between the drum and abrasive sheet carried by the drum and spaced parallel air channels in the pad extending transversely thereof for cooling the underside of the abrasive sheet, said 40 channels terminating at the ends of the pad, one edge of each channel being flared to widen the entrance to the channel and means adjacent the flared edge of the channel for deflecting air into the channel.

4. A sanding drum pad adapted for positioning between the drum and abrasive sheet carried thereby, said pad having air channels therein for cooling the underside of the abrasive sheet, and means carried by the pad for deflecting air into 50 said channels.

5. A sanding drum pad adapted for positioning between the drum and abrasive sheet carried thereby, said pad having air channels therein for cooling the underside of the abrasive sheet, 55

- means at one end of each of said channels for deflecting air into said channels and vacuum creating means at the opposite ends of said channels to accelerate discharge of air therefrom.
- 5 6. A pad for sanding drums comprising a resilient sheet of material, means for securing said sheet around the drum under an abrasive sheet carried by said drum and a plurality of air channels in the outer surface of said pad and extending diagonally thereof, one end of each of said channels constituting an air intake end and the other end of said channels constituting an air discharge end and means for accelerating the passage of air through said channels.
- 10 7. A sanding drum pad adapted for positioning

between the drum and abrasive sheet carried thereby, said pad having air channels therein for cooling the underside of the abrasive sheet, means at one end of each of said channels for deflecting air into said channels and vacuum 5 creating means at the opposite ends of said channels to accelerate discharge of air therefrom, said vacuum creating means comprising a projection at the end of the channel in advance of the channel and an inwardly extending tapering 10 recess at the trailing edge of the channel to increase the area of the channel at said trailing edge.
